FIG. 5.

UNITED STATES PATENT OFFICE

2,239,991

PRESS IRONER

Theodore R. Bush, Royal Oak, Mich., assignor to
 Borg-Warner Corporation, Chicago, Ill., a corporation of Illinois

Application February 16, 1938, Serial No. 190,833

4 Claims. (Cl. 38—25)

This invention relates to the art of laundering, with particular reference to the pressing or ironing of clothing.

As a general rule, ironing apparatus of the press or plate type has relied either upon the application of force by some mechanical force multiplying means actuated manually by the operator after juxtapositioning of the ironing elements or has employed some extraneous force applying means which is merely under the control of the operator. The first of these two methods of operation is disadvantageous in that it requires an extra movement and the exertion of extra force upon the part of the operator after the ironing elements have been placed in ironing position. The second of these two methods requires some type of more or less permanent connection to a source of power, such power being releasable by the operator to perform the pressing operation.

It is an object of the invention to overcome the disadvantages inherent in the two above-mentioned types of ironing apparatus by providing a portable press ironer which operates during the movement of the ironing elements to their ironing position to store up energy which may be released when the elements are so positioned.

A further object of the invention is to provide ironing apparatus of the character described above which may be operated with one hand so as to leave the operator's other hand free for handling the material to be pressed.

An additional object of the invention is to provide in a press ironer means whereby energy available for performing the pressing operation may be accumulated as the result of the positioning movement of the ironing elements, and to provide means whereby such energy is releasable at the will of the operator.

A further object of the invention is to provide ironing apparatus of the class described which is easily and cheaply fabricated, light in weight so as to be portable and simple to operate.

Additional objects will appear hereinafter as the description proceeds and will be pointed out more fully in the accompanying claims.

In the drawings, of which there are three sheets and which are to be understood as descriptive of the best method of practicing the invention and not as limiting:

Fig. 1 is a plan view of ironing apparatus showing the ironing elements in ironing position;

Fig. 2 is a vertical sectional view through the ironing apparatus of Fig. 1 but showing the ironing elements in their separated position;

Fig. 3 is a vertical sectional view of the ironing apparatus corresponding to Fig. 2 but showing the ironing elements in ironing relationship but prior to the application of ironing force therebetween;

Fig. 4 is a vertical sectional view corresponding to Fig. 3 illustrating the parts of the ironing apparatus after the release of ironing force;

Fig. 5 is a sectional view of a portion of the ironing apparatus shown in Fig. 4 and is taken substantially upon planes as indicated by the broken line 5—5 of Fig. 4, looking in the direction of the arrows, portions being broken away, more clearly to illustrate the invention; and

Fig. 6 is a sectional view through a portion of the ironing apparatus taken upon a plane as indicated by the line 6—6 of Fig. 4 and looking in the direction of the arrows.

Referring more specifically to the drawings, 20 the present invention will be seen to comprise ironing apparatus which has a base 10 for resting upon a table or other flat surface, such base being provided with a pedestal 12 at its forward portion for supporting an ironing element 14, 25 which may comprise a buck. The buck 14 is supported from the frame 16 of the base 10 by means of compression springs 18 interposed beneath the under surface 20 of the buck 14 and the top surface of the frame 16. Springs 18 are adapted to be initially loaded by means of bolts 22 extending through apertures in the lower buck surface 20 and in the frame 16 and being provided with a tensioning nut 24 for increasing or decreasing the initial loading.

Toward the rear of the machine the base 10 is provided with a pair of upstanding portions 26 which are adapted to receive between them the rear portion of an arm 28. A shaft 30 is secured intermediate the upstanding projections 26 by means of cap screws 32 threaded into tapped openings in the ends of the shaft 30. These cap screws may be covered as shown in Fig. 1 by decorative buttons 34. The arm 28 has spaced portions provided with apertures 36 for rotatably receiving the shaft 30.

A collar 38 is secured to the inside of one of the walls of the arm 28 by means of screws 40 and such collar has a running fit with the shaft 30.

A collar 42 is pinned to the shaft 30 at 44 and a spiral spring 46 having an inside diameter equal to or slightly less than the outside diameter of the collars 38 and 40 is disposed about these collars. One end of the spiral spring 46 is provided with a projecting portion 48 which is posi-

tioned between a pair of studs 50 secured in the wall of the arm 28 adjacent the shaft 30. The opposite end 52 of the spiral spring 46 projects into space intermediate the side walls of the arm 28 and in a position to be engaged by a foot 54 of a rotatable element 56 carried upon a shaft 58 extending transversely of arm 28 adjacent the pivot shaft 30. The pivot element 56 is maintained upon the shaft 58 against endwise movement thereon by means of cotter pins 60 extending through the shaft 58 upon opposite sides of the element 56.

A link 62 is pivotally connected at 64 to the element 56, the opposite end of the link having pivotal connection with an operating lever 66, 15 which in turn is mounted upon a shaft 68 extending transversely of the forward end of the arm 28. Operating lever 66 is provided with a handle 70 whereby it may be grasped by the operator for rotating the release element 56 to unwind the spring 46.

It will be recognized that this structure provides means for maintaining the arm in any desired position against upward or counter clockwise rotation of the arm as viewed in Figures 2 to 4 except when the spring 46 has been unwound by means of the element 56. Movement of the arm 28 in a clockwise direction is not hindered by the spring 46 as the arm 28 is then rotating in such a direction as to tend to cause the inside 30 diameter of the spring to be slightly enlarged by unwinding movement, resulting in the spring sliding rotatably over the collar 42 which is fixed against rotation upon the shaft 30. It will be recognized that any lifting movement on the forward end of the arm 28 will cause the studs 50 to rotate the projecting end 48 of the spring 46 in such a direction as to wind up and tighten the spring 46 upon its cooperating collars 38 and 42. Such tightening movement will cause the spring 46 frictionally to grip the collars 38 and 42 and resist movement of the collar 38 in a direction 40 which would permit the arm to rise.

A depending portion of the lever 66 is adapted to cooperate with a depressed portion 12 of a leaf spring 14 secured to the forward portion of the arm 28 so as to prevent accidental movement of the arm 66 in a direction to actuate the release member 56 during the pressing operation. The forward end of the arm 28 is provided with a pair of downwardly extending ears 76 which carry a pivot pin 78 for supporting a heated ironing shoe 80. The ironing shoe 80 may be heated by means of electrical elements (not shown) which receive their energy from an outlet cord 82 extending through an insulated bushing 84 into the shoe 80.

Thermostatic means may be provided for controlling the temperature of the shoe 80 and such means may be adjustable through an indicating member 86 located upon the top surface of the shoe 80. The arm 28 is maintained in its raised position by a balancing spring 88 which extends between a pin 90 secured to the rear portion of the arm 28 and a projection 92 fast upon the base 10. A nut 94 is threaded upon the end of the lower spring anchor to adjust the tension upon the spring 88.

The rear end of the arm 28 also carries a pin 96 which cooperates with a slot 98 formed in the upper end of a lever 100 pivotally mounted upon a shaft 102 secured to the upstanding rear portions 26 of the base 10 by means of cap screws 104. Lever 100 has secured thereto adjacent its lower portion a stub shaft 106 which is tightly 70 secured between a shouldered portion 108 and a nut 110 to the lever 100. Upon an enlarged portion 112 of the stub shaft 106 there is rotatably received a collar 114 which has a reduced diameter 116 for receiving a coil spring 118 of the same inside diameter as the outside diameter 116 of the collar 114. One end 120 of the spring 118 is secured intermediate a pair of studs 122 fast to the lever 100. The opposite end 124 of the spring 118 projects between a pair of ears 126 struck up from a plate 128 rotatable upon the reduced diameter 116 of the collar 114. The rotatable plate 128 abuts against a shoulder 130 formed by an enlarged diameter of the collar 114.

An additional portion 132 of the shaft 106 has an enlarged diameter received in a depressed portion on the end face of collar 114 to confine the collar against endwise movement along the shaft 106. The outer face of the enlarged diameter of the collar 114 is provided with a pin 134 which rotatably projects through an aperture in one end of a link 136, link 136 being maintained upon the pin 134 by means of a cotter pin 138. The opposite end of link 136 has pivotal connection at 140 with one arm of a bell crank 142 pivoted at 144 to an upstanding portion (not shown) of the base 10. The other arm of the bell crank 142 is pivotally secured at 146 to a depending portion 148 of the under surface 20 of the buck 14.

Plate 128 is provided with an ear to which a cable 150 of a Bowden wire 152 is pivotally secured. The Bowden wire 152 may be secured by a clip 154 in the arm 28 and is threaded through the arm 28 to project through a boss 156 integral with the lever 56. The cable 150 is provided with a button 158 adjacent the handle 70 of the lever 66 for actuation by the machine operator.

It will be understood that as the shoe 80 is moved into position over the buck 14 or from the position shown in Fig. 2 to the position shown in Fig. 3, the pin 96 rides in the slot 98 in such a manner as to rotate the lever 100 in a counterclockwise direction as viewed in Figs. 2 and 3. During this counterclockwise movement of the lever 100 the plate 128 remains stationary with respect to the collar 114 and maintains the collar against rotary movement upon the stub shaft 106. During this counterclockwise movement of the lever 100 the link 136 applies force through the pin 134 in a direction tending to rotate the collar 114 in a clockwise direction as viewed in Figs. 2 to 4; such tendency for movement of the collar 114 tends to tighten the spring 118 upon the diameter 116 of the collar 114 and prevents rotation of the collar 114 upon the stub shaft 106. This movement of the pin 134 withdraws the link 136 to the left as viewed in Figs. 2 to 4 and results in clockwise rotation of the bell crank 142 and a lowering of the buck 14 against the action of springs 18, thus increasing the compression of the springs 18. After the shoe 80 and buck 14 have assumed the position shown in Fig. 3, and with the material to be ironed located between these two ironing elements the operator may release the energy pent up in the springs 18 by pushing the button 158 of the Bowden wire and rotating the plate 128 to unwind the spring 118 through the ears 126, thereby permitting springs 18 to rotate the bell crank 142 in a counter clockwise direction and draw the link 136 toward the right as viewed in Figs. 2 to 4.

Upon completion of the ironing operation, the operator grasps the handle 70 and rotates the lever 66 in a counterclockwise direction to project the finger 54 beneath the end 52 of the

spring 46 to release the locking arrangement between the arm and base and to lift the arm 28. Lifting movement of the arm 28 rotates the lever 100 in a clockwise direction. Such rotation of the lever 100 recocks the pressure applying mechanism by rotating the collar 114 in a counterclockwise direction. Such counterclockwise rotation of the collar 114 is permitted by the spring 118 inasmuch as such rotation tends to unwind spring 118 so that the outside diameter 116 of the collar 114 may rotate within the temporarily enlarged inside diameter of the spring 118.

It is to be understood that the shoe 80 has a polished metallic pressing surface on its underside for smoothing material which may be interposed between it and the buck 14. The buck 14 is covered with a plurality of pads of absorbent padding material and a fabric facing member such as unbleached muslin to absorb moisture in the form of vapor which may be given off during the ironing operation. It is to be expressly understood that these two elements might conceivably be reversed, the buck forming the upper element and the shoe the lower element.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In a press ironer, a base, a buck carried by springs mounted on said base and operable to be moved vertically downwardly against said spring pressure, an arm pivoted to said base, a pressing shoe carried by said arm and cooperable with said buck, means connected to said arm for retracting said buck against said spring pressure, said means being operated by lowering said arm into pressing position, means for locking said arm in pressing position, means for locking said buck in depressed position and means for releasing said buck locking means.

5 2. In a press ironer, a base, a spring mounted buck carried on said base, an arm pivoted to said base for rotation about a horizontal axis, a pressing shoe carried by said arm and cooperable with said buck, means for drawing said buck against its spring mount, said means being operable by lowering said arm into pressing position, means for locking said buck in a spring-compressed position, control means for releasing said locking means, and control means for releasing said arm, both said control means being mounted on one operating handle.

10 3. In a press ironer, a base, a pressing buck mounted on said base, a pressing shoe cooperable with said buck, said shoe being carried by said base and mounted for movement toward and away from pressing relationship with said buck, means for locking said shoe in pressing relationship with said buck, pressure applying and storing means cooperable with said buck, means operable by movement of said shoe into pressing relationship with said buck to store energy in said pressure applying and storing means, and means for releasing the energy in said pressure applying and storing means when said shoe is locked in pressing relationship with said buck for applying pressure to said buck.

15 4. Ironing apparatus comprising a shoe and a buck, a frame, spring means between said frame and said buck for supporting said buck, an arm forming a pivotal connection between said base and said shoe and supporting said shoe for movement toward and away from pressing relation with said buck, means, actuated by movement of said arm upon movement of said shoe into pressing relation with said buck for moving said buck and loading said spring means, means operable for releasing said spring means when said shoe is locked in pressing relationship with said buck and a release for said arm locking means to permit movement of said shoe away from said buck.

THEODORE R. BUSH.
